SHOE-FORMING LAST.

No. 914,331.

Specification of Letters Patent. Patented March 2, 1909.

Application filed January 2, 1909. Serial No. 470,503.

To all whom it may concern:

Be it known that we, ELMER J. BLISS and EDWARD F. WHITE, citizens of the United States, and residents, respectively, of Edgartown, county of Dukes, and Quincy, county of Norfolk, Massachusetts, have invented certain new and useful Improvements in Shoe-Forming Lasts, of which the following is a specification.

10 This invention relates to lasts, especially to the kind used in the manufacture of boots and shoes and is intended to provide a simple and strong construction which will permit the last to be removed from the shoe without breaking down, stretching, or distorting the waist portion of the upper, even in cases where the last has a much greater measurement around the ball than around the waist portion. This form of last too is particularly well adapted in making special shoes for feet having bunions or enlargements of the ball joint.

20 In general the invention comprises a last whose fore part is sectionally divided by vertical dividing cuts to form a completely separable side section having sliding engagement through the agency of a slotted plate with the main section of the last so that when the last is in operative position in the shoe, it affords a strong and solid support for the 25 lasting and leveling operations, while permitting the withdrawal of the sections separately through the narrow waist portion of the shoe.

30 In the drawings Figure 1 is a side elevation, partly broken away, of a last embodying the principles of this invention. Fig. 2 is a plan view thereof partly in section; and Fig. 3 is a vertical cross sectional view on the 35 broken line as shown in Fig. 2.

35 In the practice of our invention according to the form illustrated in the drawings, the fore part of the last is divided by a central vertical cut extending longitudinally from the instep to the toe portion of the last and by a transverse vertical cut extending from the side of the last to the rear end of the longitudinal dividing wall. In this way the side section *b* is entirely severed or separable 40 from the main section *a* of said fore part.

45 In order to unite and firmly hold the two sections of the fore part together to sustain the work during the operations of lasting and leveling, we secure to the inner longitudinal face of the side section *b* a slotted plate *e*

whose rear end is open and flared as shown in Fig. 1, in order to more easily take in or receive the retaining studs *a*¹⁰ which are firmly embedded in the opposite longitudinal face of the main section *a*. The shanks of the 50 studs *a*¹⁰ are of a diameter to fit snugly in the slot of the plate *e*, while their outer end are provided with heads to keep said plate *e* snugly in contact with the vertical face of the main section *a*. As shown in Fig. 3 the 55 slotted plate *e* is inset from the vertical face of the side section *b* so as to lie flush with said surface, while a deeper channel, as shown at *b*¹⁰, is made to allow the heads of the studs *a*¹⁰ to project beyond the inner face of the 60 slotted plate *e*.

When the sections of the fore part are closed together, they form a solid continuous last block, the parts of which are firmly and strongly held together but by reason of the 65 sliding engagement between the studs *a*¹⁰ and the slotted plate *e*, the main section can be withdrawn separately from the side section and as the plane of division cuts directly 70 through the ball of the last, this results in 75 relieving the waist portion of all objectionable strain or stretch.

To prevent the parts from sticking together, and to automatically start their separation, we may provide a spring-pressed 80 plunger *a*⁸ seated in a socket formed in the transverse division wall of the main section and projecting forward so as to exert a thrust 85 or push against the rear face of the side section. Furthermore, the rear end of the side 90 section may be slightly recessed to receive the forward end of the plunger *a*⁸ so that the plunger thus accomplishes a two-fold purpose, namely, it supports the parts against displacement when the last is in normal 95 operative position, and second, it causes the parts to separate automatically when the main section is moved toward the rear of the shoe to withdraw it.

We have shown in this case the last block 100 provided with a sectional heel portion *a*² and a wedge-shaped intermediate section *a*⁴, as the divided fore part is equally applicable to a solid or to a hinged heel last.

Obviously with this principle of construction, a last can be constructed so that the 105 waist portion of the shoe will snugly fit the waist portion of the foot, while the ball portion of the foot however large, may be given ample opportunity to expand or spread.

What we claim is:—

1. A shoe-forming last embracing a fore part, divided longitudinally and vertically into a main section and a separable side section, a slotted plate secured to the vertical longitudinal face of the side section, the slot thereof being open at the rear to receive fastening members located on the opposite face of the main section, said slotted plate and 10 fastening members forming retaining means for holding the sections rigidly in operative position during the lasting and leveling operations, while permitting the separation of the parts as the last is being removed from 15 the shoe, substantially as described.

2. A shoe-forming last embracing in its construction a fore part divided longitudinally and vertically into a main section and a separable side section, the main section being 20 provided with laterally projecting studs and the side section being provided with a slotted plate having sliding engagement with said studs, said slot being open and flared at its rear end to receive the studs when the sections are assembled together, while allowing 25 their complete separation, substantially as described.

3. A shoe-forming last embracing a main section, a separable side section longitudinally divided therefrom by vertical cuts, and 30 a longitudinally movable spring-pressed plunger seated in the main section and en-

gaging a socket in the side section to hold the parts against lateral displacement, substantially as described.

4. A shoe-forming last embracing in its construction, a divided fore part embracing main and side sections vertically divided from each other, the side section being provided with a slotted plate having sliding engagement with the main section to hold the parts solidly together when the last is in operative position, and means for automatically thrusting apart the two sections when the main section is removed from the shoe, substantially as described.

5. A sectional last embracing a fore part consisting of a main section and a separable side section divided therefrom by vertical cuts, means comprising a tongue and groove 50 connection for holding said parts firmly together in operative position, while allowing their complete separation when the main section is withdrawn from the shoe, and a spring-pressed plunger arranged in the main 55 section to thrust forward the side section, substantially as described.

In witness whereof, we have subscribed the above specification.

ELMER J. BLISS.

EDWARD F. WHITE.
